UNITED STATES PATENT OFFICE.

GEORGE E. HALLENBECK, OF TOLEDO, OHIO, ASSIGNOR TO BAKER BROTHERS, OF TOLEDO, OHIO.

MACHINE-TOOL-CONTROLLING MECHANISMS.

1,235,314.

Specification of Letters Patent.

Patented July 31, 1917.

Application filed December 8, 1913. Serial No. 805,294.

To all whom it may concern:

Be it known that I, GEORGE E. HALLENBECK, a citizen of the United States, residing at Toledo, Lucas county, Ohio, have invented new and useful Machine-Tool-Controlling Mechanisms, of which the following is a specification.

This invention relates to features of operation and control incorporated in machines.

This invention has utility when embodied in power driven machines for drilling and boring.

Referring to the drawings:

15 Figure 1 is a front view of an embodiment of the invention in a machine tool;

Fig. 2 is a plan view of the driving connection for rotating the holder shaft;

20 Fig. 3 is a side elevation from the right of the showing in Fig. 1;

Fig. 4 is a side elevation from the left of the showing in Fig. 1;

25 Fig. 5 is a detail view of the actuator or hand lever for shifting the gears to cause speed changes;

Fig. 6 is a plan view, with parts broken away, of the compound table;

Fig. 7 is a fragmentary view of the holder feed speed change mechanism;

30 Fig. 8 is a fragmentary view of another speed change mechanism for the holder feed;

Fig. 9 is a detail of transmission elements in the holder feed to take care of unusual 35 resistance to feeding of the holder; and

Fig. 10 is a plan view of the guide for the actuator hand lever of Fig. 5.

The driving belt 1, when shifted from the loose pulley 2 serves to rotate the pulley 3 40 fast on the shaft 4 mounted in the gear housing 5. On the inner portion of this shaft 4 is mounted the bevel gear 6 (Fig. 4) in mesh with the bevel gear 7 on the shaft section having fast therewith the gear 8 in 45 mesh with the gear 9 on the parallel sleeve or shaft section 10, which also has fast therewith the gear 11.

To connect up the machine tool for driving, the disk 12 may be grasped to reciprocate the shifting element 13 having the fork 14 embracing the gear 15 having fast therewith the clutch 16. The gear 15 and clutch 16 are splined on the shaft 17 alined with the shaft section carrying the gears 7, 8.

With the clutch 16 shifted for direct connection to the shaft section carrying the gear 8, the shaft 17 is driven at a higher speed than when the gear 15 is shifted to be in mesh with the gear 11.

The shaft 17 has distributed therealong 60 bearings 18 to insure easy running at any position of transmission strain. A bearing 18 is disposed between the pairs of gears 19, 20, and 21, 22, fast on the shaft 17.

For additional variable speed driving, the 65 actuator 23 is a convenient controller. This hand lever 23 has the rocking bearing 24 to permit oscillation toward and from the machine gear housing 5, and the fulcrum bearing 25 to permit oscillation transversely as 70 to the front of the machine. The hand lever 23 carries the studs or pins 26, 27. By rocking the hand lever 23 upon its bearing 25 (Figs. 1, 3, 4, 5), the stud 27 may engage the shifting element 28, and then oscillation 75 of this hand lever 23 on its bearing 24 may reciprocate the shifting element 28 so that its fork 29 may move the gears 30, 31, splined on the shaft 32, to drive the shaft 32 respectively from the gears 19, 20 on the 80 shaft 17. A second pair of shiftable members or gears may be actuated by rocking the hand lever 23 to cause the stud 26 to engage the shifting element 33 carrying the fork 34 embracing the pair of gears 35, 36 85 splined on the shaft 32 and movable respectively to mesh with the gears 21, 22. The rotation of the shaft 32 is at slower speed as the driving connection approaches the gear 22.

The shaft 32 (Fig. 4) carries the bevel gear 37 in mesh with the bevel gear 38 on the shaft 39 which carries the pinion 41 (Fig. 2) in mesh with the gear 42 on the holder shaft 43. These shafts are carried 95 by the machine tool frame 40.

The variable speed drive may bring about eight speeds of rotation of the holder shaft 43 carrying the holder 44 for the working tool 45.

The lower portion of the vertical shaft 39 carries the bevel gear 46 (Fig. 4) in mesh with the bevel gear 47 on the shaft 48 having fast thereon the gears 49, 50, 51, respectively in mesh with the loose gears 52, 53, 105 54, on the sleeve 55 (Fig. 7). On the side of the frame 40 adjacent the position of the operator is the plate 56, having stop posi-

tions 57, 58, 59 for the crank arm 60 connected by the gear 61 in mesh with the teeth 62 on the shaft 63. Within the gears 52, 53, 54, and in the split or slotted end of the shaft 63 is mounted the dog 64 yieldably actuated by the spring 65 moving the plunger 66 to cause the heel 67 to throw the dog 64 through the slot 68 into key ways 69 of the loose gears 52, 53, 54. With the crank arm 60 at position 57, the dog 64 is in position to connect the gear 54 for driving the shaft 55. Similarly position 58 will connect the gear 53, and position 59 the gear 52. The showing in Fig. 7 is during a change between connecting the gears 53, 54.

15 There is accordingly provided three speed change speed mechanisms for driving the gear 70 in mesh with the bevel gear 71 (Figs. 4, 9) on the shaft 72 carrying the pinion 73 in mesh with the transmission element or gear 74 clamped between the frictional holding means or fiber disks 75 on the fiber sleeve 76 disposed on the sleeve 77 keyed to the shaft 78. The frictional fiber holding means serves to normally lock the element 74 in transmission engagement to drive the shaft 78, by the washer 79 clamped in position by the nut 80.

20 The shaft 78 has on its opposite end (Fig. 3) the bevel gear 81 in mesh with the gear 82 on the sleeve 83 (Fig. 8) carrying the pinion 84. The pinion 84 is in mesh with the gear 85 on the countershaft 86 which also carries the gear 87 in mesh with the gear 88 loose on the sleeve 89. The pinion 84 or the gear 88 may be keyed to the sleeve 89 by the dog 64 by grasping the disk 90 and reciprocating the shaft 63. This is a second variable speed drive in the transmission from the shaft 39. While there may be the power driving at these six speeds of the sleeve shaft 89, delicate manual setting may be had through the hand wheel 91 for driving the worm gear 92 in mesh with the worm wheel 93 on the shaft 94 (Fig. 3). This shaft 94 may be actuated for quick and wide adjustments by the arms 95. Rotation of the shaft 94, through the gear 96 engages the rack 97 to reciprocate the holder 44. 25 While the driving through the shaft 43 serves to rotate the holder 44, the driving through the two variable speed mechanisms and yieldable transmission element to the shaft 94 controls the feed. For quick adjustments over a wide range, the arms 95 may be used for manual shifting, while more refined adjustments may be made from the hand wheel 91. During the adjustments through the arms 95, the key 64 may be 30 in a disconnecting position to release the worm 92.

Opposing the tool 45 is the compound table upon which the work may be accurately positioned and shifted quickly and conveniently. The front of the machine

35 frame 40 has the slide guide 98 for the first adjustable table section or bracket 99. For adjusting this section or bracket 99 it carries the shaft 100 having the bevel gear 101 in mesh with the bevel gear 102 on the screw 103 operable in the pedestal 104. By rotating the shaft 100 with a wrench or crank the bracket 99 may be adjusted up and down along the slide 98.

40 Mounted on the first table section 99 for adjustment toward and from the machine frame 40 is the second adjustable table section 105. This section 105 carries the shaft 106 (Fig. 6) which may be released for rotation by disconnecting the clutch collar 107. Rotation of the hand wheel 108 causes the shaft 106 to rotate in its inner bearing 109 and through the pinion 110 drive the bevel gear 111 also mounted in the bearing 109 of the section 105. This bevel gear 111 has nut connection with the screw 112 which may be held from rotation by the clutch collar 113. When this screw 112 is locked by the collar 113 to the bracket 99, the unclutching of the shaft 106 may effect adjustment of the section 105 toward and from the frame 40. While with the clutch 107 connected, a wrench or crank may be used to rotate the shaft 112 and secure similar adjustments of the section 105.

45 Mounted for adjustment transversely across the section 105, is the third adjustable table section 114. The section 105 carries the shaft 115 which may be released for rotation by disconnecting the collar 116. Rotation of the shaft 115 by the hand wheel 117 in its inner bearing 118 carried by the section 105, drives the bevel gear 119 in mesh with the bevel gear 120 also in the bearing 118. This bevel gear 120 has nut coaction with the screw shaft 121. This shaft 121 may be locked from rotation as to the section 114 by the clutch collars 122. When this shaft has its clutch collars disconnected, adjustment of the section 114 may be had by rotating the shaft 121 by a wrench or crank, with the shaft 115 locked. With the shaft 121 locked, and the clutch 116 released, adjustment of the section 114 may be readily effected from the hand wheel 117.

50 The actuator 23 is guided in its double rockings by the plate 124 having the way 125, for holding the pin 27 in engagement with the shifting element 28, the way 126 for holding the pin 26 in engagement with the shifting element 33. The intermediate way 127 (Fig. 10) precludes disconnection of the hand lever 23 from a shifting element until the shifting elements are in central disconnected position.

55 In operation, the control mechanisms are all adjacent the front of the machine where the operator may best observe the work and control the machine in handling such work. The hand wheels 108, 117, permit ready

initial placing and adjustment of work, and without changing his position, the operator may connect the machine up for driving, by the disk actuator 12 and hand lever actuator 23. Change of speed through these actuators may preserve proportional feed rate for the holder as to the rotation drive of the holder. The proportional feed rate for the holder may have the wide range permitted 5 by the two variable speed mechanisms controllable through the crank arm actuator 60 and the disk actuator 90. Settings of the holder for feed operation may be conveniently made and quickly by the arms 95 and 10 the hand wheel 91, the latter for closer work. Should the feed rate selected be excessive, to the point of endangering the transmission, or should extreme hardness or other unusual resistance be met in the feed travel 15 of the holder, slippage is permitted at the frictional holding of the transmission element 74.

A special feature of utility of the machine disclosed is its ready adaptation for finishing work, for instance in drilling the particular speed may be given the drill for which the material will best care and the feed rate therefor. With this much of the problem solved the rough drilling done, 20 reaming may occur by merely changing tools and then the handle or disk 90 may be grasped and the feed speeded up by pulling the dog 64 into driving engagement through the chain of gears 84, 85, 87, 88. This increased speed may be the proportional higher 25 rate conditions will stand for reaming as against the drilling and involves no working out of the complexities as to the main variable speed driving gears or the variable 30 speed driving gears in the feeding mechanism including the gears 49, 50, 51, 52, 53, 54. This is a feature having considerable merit in practice for these two main variable speed driving trains may be left undisturbed and still the maximum utility simply attained upon introduction of the reamer 35 by the single operation of the disk 90.

What is claimed and it is desired to secure by Letters Patent is:

50 1. A machine tool embodying a frame, a rotary spindle reciprocable in said frame, and spindle driving means including a non-reciprocable shaft laterally of the spindle, a pair of shafts extending away from the spindle, and variable speed gearing between the pair of shafts.

2. A machine tool embodying a frame, a rotary spindle reciprocable in said frame, and spindle rotation driving means including a non-reciprocable shaft laterally of the spindle, a pair of shafts extending away

from the spindle, and variable speed gearing between the pair of shafts.

3. A machine tool embodying a frame, a rotary spindle reciprocable in said frame, 65 spindle rotation driving means, and extending therefrom, spindle reciprocation driving means including a pair of shafts extending away from the spindle, and variable speed gearing between said shafts. 70

4. A machine tool embodying a frame, a rotary spindle reciprocable in said frame, and spindle rotation and reciprocation driving means, said rotating driving means including a pair of shafts extending away 75 from the spindle and said reciprocation driving means also including a separate pair of shafts extending away from the spindle, and variable speed gearing therebetween.

5. A machine tool embodying a frame, a vertical spindle in said frame, a pair of parallel shafts extending away from said spindle, variable speed gearing between said shafts, and connections from one of said shafts independently of through the spindle 80 for varying the feed travel of said spindle.

6. A machine tool embodying a frame, a vertical spindle in said frame, a pair of horizontal parallel shafts extending away from said spindle, variable speed gearing between 90 said shafts, and connections from one of said shafts independently of through the spindle for varying the feed travel of said spindle.

7. A machine tool embodying a frame, a horizontal driving shaft in said frame, a vertical spindle spaced therefrom, parallel shafts extending from adjacent the spindle toward the driving shaft, variable speed gearing between said shafts, and driving connection from one of said shafts independently of through the spindle for varying 95 the feed travel of said spindle. 100

8. A machine tool embodying a frame, a drill spindle in said frame, a spindle rotation actuating shaft adjacent said spindle 105 and parallel thereto, and spindle feeding mechanism actuatable from said shaft.

9. A machine tool embodying a frame, a drill spindle in said frame, a spindle rotation actuating shaft adjacent said spindle 110 and parallel thereto, parallel shafts extending from said shaft, and variable speed gearing between said parallel shafts, said parallel shafts being connected to vary the feed travel of the spindle. 115

In testimony whereof I affix my signature in the presence of two witnesses.

GEO. E. HALLENBECK.
